UNITED STATES PATENT OFFICE

MARIE WILLIAM KRAUTH, OF HAMILTON, OHIO, ASSIGNOR TO KRAUTH & BENNINGHOFEN, OF HAMILTON, OHIO, A FIRM

SHEET HOLDING RACK

Original application filed May 17, 1928, Serial No. 278,596. Divided and this application filed August 23, 1930. Serial No. 477,273.

This invention relates to music stands and is particularly directed to a collapsible, foldable rack for supporting sheets or books of music etc. The present application is a division of an abandoned application of 5 Marie William Krauth, Serial No. 278,596, filed May 17, 1928, the latter being copending at the time this application was filed. The co-pending application is directed to 10 the features of a support or tripod for a music stand. The music stand disclosed in the pending case includes the base or support for a post supporting a rack of the present nature on the upper end of the post. 15 The rack of this invention is generally applied to this type of music stand; although its application to this type of supporting means is intended to be included in view of those features of invention residing entirely 20 in the rack or holder.

It is, therefore, an object of this invention to provide a music rack of foldable construction which is readily and easily collapsible into compact form. Another 25 object in connection with the foregoing is to provide that the music stand is highly efficient and that its utility and stability are in no way detracted from by the fabrication thereof permitting compact folding.

Another object of this invention is to provide an adjustable mounting for the sheet holding rack wherein the same is pivotally mounted to its attaching stand or post and in which the swinging or adjustment movement of the rack is limited and the rack is 35 positively maintained against accidental displacement at any selected inclined position within its range of adjustment without the necessity of drawing up a clamp for 40 each setting.

Other objects and certain advantages will be more fully apparent from the description of the accompanying drawing in which:

Figure 1 is a front view of a music stand 45 incorporating the improved sheet holding rack.

Figure 2 is a sectional view taken on line 2-2, Figure 1, detailing the adjustable mounting of the rack.

Figure 3 is a front view of the rack show-

ing the same in partially collapsed or folded position.

Figure 4 is a rear view of the adjustable connection between the rack and its attaching post.

Figure 5 is a sectional view taken on line 5-5, Figure 1, detailing the means for aligning the sections of the diagonal straps.

Referring to the drawing, the rack 10 is shown mounted upon an extensible post 11 60 mounted on a tripod 12. The post is made up of a plurality of tubular sections 13 which decrease in diameter from the base to the upper section for the purpose of successively completely telescoping into each other 65 into a length represented by the length of one section. The construction of the tripod and post are of no importance in the present case except as an instance of a support for the rack.

The music holding rack 10 includes a main central strap 14, from the bottom of which strap, and in respective directions, angle iron rests 15 extend outwardly being pivoted to the central strap. The corresponding flanges 16 of these angle iron pieces constitute ledges for supporting the sheets. The back rest for filling out the rack and maintaining the ledges or sheet rests in sheet supporting position comprises 80 a multiplicity of strap iron lengths of relatively small dimension. These strap lengths are suitably pivoted to permit a complete collapsing of the rack when the rests are folded up along the central strap.

Describing the rack in set up position, a pair of top straps 17 have their adjacent ends pivotally attached to the upper end of the center strap and extend outwardly parallel to the rests at the bottom of the rack. 90 The respective outer ends of these top straps 16 and the adjacent ends of the rests are pivotally connected together by means of sectional side straps 18. The straps are each formed of a long upper section 19 and 95 a short lower section 20 pivotally linked together. The rests and the straps in this arrangement form a rectangular back for the rack.

Sectional diagonal brace straps 21 are pro- 100

vided, each strap being pivoted to the respective pivot point of the side straps and top straps at corresponding ends and having their other ends pivotally attached to the base or center strap slightly above the pivots of the rests as at 22. The pivotal attachment of the respective formed sides of the rack formed by the linkage described is two independent pivots at each side of the base strap so that the rack sides or halves fold over the adjacent side portions of the base strap. In other words, the rack sides fold on each side of a central line (see Figure 2). The diagonal straps 21 are each formed of a pair of sections of equal length pivoted together by pivot pins 23. The joining end of a section of each diagonal strap extends slightly beyond its pivot pin 23 and has an indentation 24 formed therein in cooperating with an indentation 25, formed in the adjacent face of the aligned companion section providing a detent for a snap setting of the sections in aligned bracing position when the indentations 24 and 25 are registered (see Figure 5).

The center strip is depressed over that portion 14^a between the rest pivots and the top strap pivots, this depression forming a clearance for the folded sections of diagonal straps when the rack is collapsed since these straps are placed in back of the top and side straps and pivoted to the central strap on the depressed portion.

To collapse the rack, the diagonal brace straps are broken centrally on their section joining pivots 23 upwardly and the side straps are broken at their section joining pivots outwardly (see dot and dash lines of Figure 1). The outer corners of the rack, that is, the juncture of the top straps and side straps, are then swung on an arc downwardly, described from the inner pivots of the top straps.

As shown in Figure 3, continued movement in the directions above described will enable the rack to be folded or collapsed into a length slightly shorter than the length of the base strap and of very slightly greater width than the base strap.

The attachment of the rack to the extensible post is by means of a short post 26 adapted to be inserted into the upper end of the main post of the music stand or into any type of holding socket. This post is limited in its insertion by means of a pressed portion 27 widening the post slightly at an intermediate point. The extreme upper end of the post 26 is pivotally attached, by means of a pivot pin 28^a, to the upper end of an angle iron bracket 28 secured to the back of the central strap 14 substantially centrally of the length of the strap. An adjustable brace 30 is pivotally attached to the lower end of the bracket by a pivot pin 31, and the outer end of the brace is pro-

vided with a slot 32. This slot 32 is traversed by a screw 33 engaged into the post. Felt or leather washers 34 are disposed between the screw head and the brace, and the screw is riveted after being screwed down to such degree as to allow a frictional engagement of the brace between the washers and the body of the post.

By this three point pivotal attachment and the slight binding effect of the brace relative to the screw, the rack is not easily dislodged from a set position. Furthermore, as there would be a tendency for the pivot pins 28^a, 31 to wear and become loose during continued usage, the binding effect of the brace engaged between the washers and the post will always have the effect of frictionally automatically maintaining the rack in set position.

Having described my invention, I claim:

A foldable sheet holding rack comprising a center bar, a rest pivoted to the base of the center bar to move from a position parallel with said center strip to a position at right angles thereto, an upper bar pivotally connected to the top of the center bar and adapted to move in the same manner as the rest, a side bar, comprising, sections hinged together, said side bar pivotally connecting the respective outer end of the rest and top bar, a diagonal brace, comprising, sections hinged together, said brace pivotally connected to the lower end of the center bar and to the diagonally opposite connection of the upper bar and side bar, each of said hinged sections, making up the rack, being disposed in a different plane so as to swing freely on their pivots, and said center strip being centrally depressed so as to provide a portion also in a different plane.

In witness whereof, I hereunto subscribe my name.

MARIE WILLIAM KRAUTH.
